UNITED STATES PATENT OFFICE.

FRIEDRICH WILHELM BERGMANN, OF BARMEN, GERMANY.

OVEN.

SPECIFICATION forming part of Letters Patent No. 434,577, dated August 19, 1890.

Application filed December 14, 1888. Serial No. 293,651. (No model.) Patented in Germany January 12, 1888, No. 44,197; in England November 8, 1888, No. 16,180; in Belgium November 8, 1888, No. 83,881; in Italy November 20, 1888, No. 24,476/341, and in Austria-Hungary June 5, 1889, No. 45,530 and No. 7,868.

To all whom it may concern:

Be it known that I, FRIEDRICH WILHELM BERGMANN, of Barmen-Wupperfeld, in the Kingdom of Prussia and German Empire, have invented new and useful Improvements in Ovens, (for which I have obtained patents, as follows: in Germany, No. 44,197, dated January 12, 1888; in Austria-Hungary, No. 45,530 and No. 7,868, dated June 5, 1889; in 10 England, No. 16,180, dated November 8, 1888; in Belgium, No. 83,881, dated November 8, 1888; and in Italy, No. 24,476/341, dated November 20, 1888,) of which the following is a specification, reference being had therein to the accompanying drawings.

This invention relates to ovens applicable for baking, japanning, drying, &c., and has for its objects, first, to enable the oven to be heated by gas; second, the prevention of soot 20 accumulating in the flues; third, to enable the oven to be taken to pieces, and, fourth, to enable the heating-chamber of the oven to be enlarged or diminished.

An oven according to this invention is represented in the annexed drawings.

Figure 1 shows the mode of erecting an oven according to this invention in longitudinal section. Fig. 2 shows a plan section of the same, taken on the line 1 1 of Fig. 1; 30 Fig. 3, a plan section taken on the line 2 2 of Fig. 1; Fig. 4, a vertical section of an oven modified in construction, on the same section line as Fig. 1, and Fig. 5 a similar section with some further modifications.

I will proceed to describe in detail the construction and operation of an oven embodying my invention, and will then point out more definitely in claims the particular improvements which I believe to be new and 40 wish to secure by Letters Patent.

In the drawings, *a* represents the fire-place of the oven, above which there is arranged a retort *p*, which is covered by a heating-plate *o*. The retort *p* has openings *p'* in its sides, 45 and coal being placed in the retort and heated by the fire below gases will be thrown off, which escape from these side openings into flues *t* at each side. The side walls *f* of the fire-place turn outward at their upper por-

tions and are developed into plates *d*, which 50 extend outward horizontally to the sides of the oven and cover the space below, forming chambers *c'*. In Fig. 1 of the drawings these chambers do not extend outward to the sides of the oven; but between them and the outer 55 wall *v* of the oven there are two chambers or spaces *c*², in which the soot is deposited, as will be hereinafter described. In Figs. 4 and 5 of the drawings this construction is modified by dispensing with the partition making 60 two chambers, so that the chamber *c*, in which the soot is deposited, occupies the entire space between the outer wall and the fire-place.

Above the heating-plate *o* is a heating-chamber *l*, which is surrounded by the flues *t* below, *t'* at the sides, and *t²* above the chamber, the last-named flues extending from side to side and communicating with the side flues. A diaphragm or division-plate extends entirely across the oven immediately over the 70 flues *t²*, and above it may be arranged a second heating-chamber *l'*, underneath which are the flues *t³*, communicating with the side flues, and also communicating with the flues *t²* below, by means of central openings *s* in 75 the diaphragm, which are regulated by sliding dampers of any ordinary construction. The lower flues *t* communicate with the side flues *t'*, and if more than one heating-chamber 80 is employed the passage of the hot gases is thence up through the openings *s* and outward through the flues *t³*, again into the side flues, thence upward into the top flues *t'*, and out through a central exit-flue *w*, which is 85 regulated by an ordinary damper *x*, this being the direction of the draft, the force of which is regulated by the dampers at the openings *s* and the exit-damper *x*. The passage from the lower flues *t* to the side flues *t'* is partially obstructed by soot-arresters *c* for 90 the purpose of stopping the soot which may be carried along with the gases from the fire-place. This may be done in various ways. In Fig. 1 vertical walls are shown at the junction between the two flues, through which 95 there are perforations or openings for the passage of the gases. In Fig. 4 angular plates are shown at this junction, the horizontal por-

tions of which partially close the lower ends of the side flues, and in Fig. 5 are upright plates similar to those in Fig. 1, but without any perforations. In all these cases there are openings 5 in the plates *d* immediately in front of these soot-arresters downward into the soot-receivers, so that the soot caught or arrested by these devices will drop into the receivers below, whence it may be removed at pleasure.

- 10 In the construction shown in Fig. 5 of the drawings this opening in the plates *d* extends outward beyond the upright soot-arresters, so that the circulation is downward through the openings in front and thence upward into the 15 side flues. The circulation in each case is indicated by arrows in the respective figures.

The oven is constructed in sections, so that each heating-chamber will be in a separate section, and the sections are constructed so

- 20 that they can be placed one above another in any number desired. Each section is provided at its upper edge with a surrounding flange *z*, which extends somewhat above the wall of the section to which it is attached, so 25 as to receive the lower portion of the next section above. The sections are thus held together and the joints between them covered.

The dampers governing the openings *s* are provided with suitable handles *n*, to which 30 the usual rods may be attached and extended to the outside of the oven for the purpose of moving the dampers.

A door *b* at the base of the oven and at one side thereof opens into the fire-place, and 35 there are of course the usual doors provided for opening into the heating-chambers.

If it is desired to provide an oven with a larger heating-chamber than the chambers *l* or *l'*, two sections are used without the horizontal middle flues *t²* *t³*, and with no top to the lower one or bottom to the upper one, and the horizontal diaphragm or division-plate is removed. The two sections are then arranged as already described, thereby forming one 45 large heating-chamber, as shown in Fig. 4 of the drawings, in which there are bottom flues *t*, side flues *t'*, and upper flues *t⁴*, opening into the exit-flue *w*, without any cross-circulation midway of the oven, like that provided for in 50 Figs. 1 and 5 of the drawings.

When the oven is constructed as shown in Fig. 1 of the drawings, with chambers *C'* between the fire-place and the outer walls, the heat generated is better retained in the fire-place by reason of the intervening chambers.

To put the oven in operation the retort *p* is charged with coal and a fire is started and kept burning on the fire-place *a*, which heats the retort and coal therein. Coal gases are 60 generated by the heat within the retort, and escaping through the openings *p'* are ignited by the fire in the fire-place below, thus greatly increasing the heat. The highly-heated gases pass from the lower flues *t* into the rising

side flues *t'*, the arresters *c* stopping the soot 65 which will be driven against them and causing it to drop into the receiving-chambers below. The hot gases pass up the side flues *t'* and thence into the cross-flues *t²*, through the openings *s* into the flues *t³* of the next section, and thence out to the side flues again and up to the exit-flue, as already described; or when there is but one large heating-chamber the gases pass directly up the side flues to the upper flues *t⁴* and exit-flue, as already 70 75 stated.

Changes may be made in some details of construction and arrangement, and I do not wish to be understood as limiting myself to the precise details herein shown and described.

What I claim, and desire to secure by Letters Patent of the United States, is—

1. In an oven, the heating-chamber, in combination with the side flues *t'*, arranged on two opposite sides of the chamber, the fire-place *a*, arranged centrally below the heating-chamber, a retort *p*, arranged just above the open top of the fire-place, parallel to the sides of the oven, provided with flues, and having openings *p'* along its sides, and flues *t*, arranged one on each side of the retort and leading from the fire-place below the latter outward and underneath the heating-chamber to the respective side flues *t'*, substantially as 90 95 and for the purposes specified.

2. In an oven, two or more heating-chambers *l* *l'*, arranged one above the other, in combination with the side flues *t'*, the two horizontal flues *t²* *t³*, arranged between the heating-chambers and extending from one side flue to the other, the partition between the flues *t²* *t³*, provided with openings *s*, arranged centrally of the chambers, dampers for opening and closing said openings, the fire-place *a*, arranged centrally below the chambers, and the flues *t* at the bottom of the oven leading outward therefrom to opposite sides of the oven and connecting respectively with the side flues *t'*, substantially as and for 100 105 110 the purposes specified.

3. In an oven, the heating-chamber, in combination with the side flues *t'*, the fire-place *a*, arranged centrally below the heating-chambers, the bottom flues *t*, running outward from the fire-place and connecting respectively with the said side flues, the soot-spaces *c²*, arranged underneath the flues *t*, having a connection with the latter near their outer ends, and the soot-arresters *c*, substantially as and 115 120 for the purposes specified.

In witness whereof I have hereunto set my hand in presence of two witnesses.

FRIEDRICH WILHELM BERGMANN.
